UNITED STATES PATENT OFFICE.

NORTH DOWLING, OF PHILADELPHIA, PENNSYLVANIA.

TELEPHONE-TRANSMITTER.

SPECIFICATION forming part of Letters Patent No. 335,511, dated February 2, 1886.

Application filed February 14, 1885. Serial No. 155,925. (No model.)

To all whom it may concern:

Be it known that I, NORTH DOWLING, a citizen of the United States, residing in the city and county of Philadelphia, and State of Pennsylvania, have invented certain new and useful Improvements in Telephone-Transmitters, of which the following is a full, clear, and exact description, reference being had to the accompanying drawings.

- 10 This invention relates, generally, to improvements in the class of telephone-transmitters of which the "Blake transmitter" is an example. It is a modification, in certain respects, of an improvement in transmitters of the said class for which I filed an application for Letters Patent February 14, 1885, Serial No. 155,924, and I hereby disclaim all devices embraced in the present application which are claimed in said above-mentioned application.
- 15 20 In the latter device I relied solely upon the force of gravity to regulate the contact between the carbon button and the platinum bead of the diaphragm-plate. In the present instance I use an adjustable magnet in connection with a carbon-bearing arm or pivoted lever for regulating the carbon-platinum contact.

I shall now proceed to describe one mode, the best that has occurred to me, of carrying 30 out the invention, reference being had to the annexed drawings, of which—

Figure 1 is a front elevation of the transmitter-box, looking into the same, the lid or door having been thrown open. Fig. 2 is a 35 section, enlarged, as on line *a b*, Fig. 1, with the lid closed. Fig. 3 is a section as on line *c d*, Fig. 1, looking in the direction of the adjacent arrow.

40 A is the transmitter-box, to the inside of the lid B of which is secured the diaphragm-plate C, with the platinum bead D, Figs. 2 and 3, secured by a disk, *x*, fastened to the diaphragm, and of usual construction.

45 E E' are the respective arms of a bell-crank lever, which is nicely pivoted upon trunnions or cones F, Fig. 3, whose points enter sockets in the ends of two opposite adjusting-screws, G, Figs. 1 and 3, that pass through holes in flanges *h* of a plate, I, that is connected with 50 one of the wires *w* leading to the usual battery. (Not shown.) Arm E extends over the dia-

phragm C, and bears at or near its free end, over the platinum bead D, a carbon sleeve or button, J. The other wire, *w'*, of the battery-circuit connects the platinum bead with the primary 55 coil of the helix K, contained within the transmitter-box, and the wires *w* of the secondary of the inductorium connected with the line as usual.

Thus far the construction is similar to that 60 of my gravity-regulator described in the application to be made for a patent hereinbefore referred to; in fact, the present device requires but an adjustable counterpoise in lieu of the magnet hereinafter mentioned, to be 65 applied to the arm E', to be identical therewith. I substitute, however, for the said counterpoise, a magnet, M, permanent or electro, which, in the present instance, is a horseshoe-magnet. This is secured loosely to the inside 70 of the bottom of the transmitter-box by means of straps *l*, so as to allow it (the magnet) to be slid to and fro. The position of the latter, as shown, is such that its ends or poles, which are substantially at right angles to the 75 arm E' when the door is closed, (see Fig. 2,) may be brought in proximity with the latter. It will of course be understood that this arm E' is of iron, in order to constitute an armature to the magnet. I prefer to make the same of 80 flattened wire with its free end bent into a rectangular loop, as *o*, so as to extend across the field of the poles of the magnet.

As a means of adjusting the magnet to and 85 from the arm E', I employ in connection with the former a screw, N, that works in a threaded box, P, fixed on the lower side of the transmitter-box. When the button *q* on the outside is turned, the magnet is forced forward or retracted, as required.

90 The operation of the device is apparent, as it is quite obvious that the nearer the poles of the magnet are brought toward the loop of the pivoted bell-crank arm E' the more strongly will the latter be drawn to the magnet, and 95 consequently the greater the pressure of the carbon button at the end of the other arm, E, of the bell-crank against the platinum point, and the converse. The spring *y* bears lightly 100 against the arm E, and while it does not hold the contact-point away from the diaphragm it prevents the arm from vibrating too violently,

and thus producing a rattling noise at the receiver, which would interfere with distinct articulation.

What I claim, and desire to secure by Letters Patent, is—

The combination, in a telephone-transmitter, of the diaphragm and platinum point, the carbon-bearing lever, and the armature-arm, the permanent sliding magnet and adjusting-screw, and the flat spring bearing against the

carbon-bearing lever, the whole arranged as described, whereby the mechanism may be accurately adjusted, substantially as specified.

In testimony whereof I have hereunto affixed my signature this 17th day of January, 15 A. D. 1885.

NORTH DOWLING.
